UNITED STATES PATENT OFFICE.

GEORGE GODDU, OF WINCHESTER, MASSACHUSETTS, ASSIGNOR TO UNITED SHOE MACHINERY CORPORATION, OF PATERSON, NEW JERSEY, A CORPORATION OF NEW JERSEY.

FASTENING-INSERTING MACHINE.

Application filed November 15, 1924. Serial No. 750,200.

This invention relates to the manufacture of shoes and particularly to means for controlling and guiding a strip of material during the performance of an operation 5 thereon.

In the manufacture of shoes it is frequently necessary to attach a strip of material, for example randing or welting, to another shoe part or parts, and it is an object 10 of the present invention to provide improved means for guiding and controlling such a strip of material as it is fed to and past the fastening-inserting instrumentalities. With this object in view, a feature of the invention 15 consists of a novel gage member located adjacent to the operating instrumentalities of the machine, arranged to engage an edge of a strip of material to guide the strip of material to the operating instrumentalities 20 and forming an abutment against which the strip of material may be bent as it is passed through the machine. In the herein disclosed machine, and in accordance with a further feature of the invention, a second 25 gage member provided with an open-ended slot cooperates with the first, limiting the movement of the strip away from the first.

With the above and other objects and features in view the invention will now be described with reference to the accompanying drawings and pointed out in the claims.

In the drawings,

Fig. 1 is a perspective view of a portion of a fastening-inserting machine provided 30 with strip-positioning means in accordance with the present invention;

Fig. 2 is another perspective taken from a different viewpoint; and

Fig. 3 is a side elevation of portions of the 40 same device with certain parts of the machine and of the work in cross-section.

The invention is disclosed herein as embodied in a nail-inserting machine of the type disclosed in United States Letters Patent No. 490,624, granted January 24, 1893 on an application of Louis Goddu, although the invention is not limited to use in a machine of this type.

Such a machine is provided with an awl 50 10 operated to penetrate and feed the work, a driver 12 which inserts nails in the openings formed in the work by the awl 10, and an abutment 14 often spoken of as a "guard

plate cap" against which the work is forced during the insertion of the nails by a work 55 support comprising a horn 16 and suitable operating instrumentalities therefor. Machines of the character disclosed in said United States Letters Patent No. 490,624 are commonly used for inserting a series of nails 60 about the periphery of shoe parts to secure such parts permanently together. Such a machine is often provided with a gage against which the shoe upper, whether counter, shank or forepart, may be positioned as 65 the fastenings are inserted. This gage often, and as herein illustrated, comprises a roll, shown at 18, adjustably carried by a slide or carriage 20 (Fig. 2). As illustrated, carriage 20 may be moved toward and from the 70 line of drive of the driver 12 by means of rack and pinion mechanism provided for that purpose. Thus carriage 20 is provided with a rack bar 22 meshing with a pinion 75 24 carried by a shaft 26 suitably journaled in bearings formed in or carried by guard plate cap 14 or other suitable part of the machine. Conveniently a handle 28 is formed as an extension of shaft 26, rotation of which will move gage roll 18 toward and 80 from the line of drive.

Any suitable means may be used to guide the carriage 20 as it is adjusted back and forth and to secure it to the guard plate cap 14. Moreover, since it may be desired to 85 vary the elevation of roll 18, that roll is illustrated as removably clamped to the forward end of a lever 30 fulcrumed at 32 to carriage 20, a rearward extension of lever 30 being formed with a slot 34. A screw 36 90 carried by carriage 20 passes through slot 34 and is provided at its lower end with an adjusting nut 38. A pair of springs 40, 42 surround screw 36 and bear against washers contacting with opposite faces of lever 30 95 adjacent to slot 34. Thus roll 18 is yieldingly held against undesired vertical movement but may be adjusted vertically by movement of nut 38.

The illustrated strip-controlling and positioning mechanism which will now be described, is arranged to cooperate with the gage roll 18 and with the fastening-inserting instrumentalities of the machine. Thus a gage member 48 is adjustably secured to the 100 side of guard plate cap 14 by a screw 52

passing through a slot 53 formed therein. This gage member is provided with a slot 54 having a closed end 56 and an open end 58. Cooperating therewith and arranged in effect to vary the position of the closed end of the slot is a gage member 60 formed with a slot 62 through which passes a screw 50 thus securing member 60 in adjusted position relatively to member 48. The strip of material, illustrated as randing, which is to be fastened in place passes through slot 54, the position of gage member 60 depending upon the width of the strip of material and the desired distance from its edge at which the fastenings are to be inserted. Similarly gage roll 18 may be adjusted to determine the distance at which the fastening shall be inserted from the edge of the work piece to which the strip is to be attached.

20 In attaching a strip of randing or welting to a shoe part having a convexly curved edge, whether a sole or a heel, it is ordinarily necessary to bend the randing or welting as it is applied. To facilitate this, there is provided a gage member engaging an edge of the strip on the inside of the curve about which the strip is bent. Thus the illustrated construction includes a button gage 70 in front of the fastening-inserting instrumentalities having a thin periphery but a thicker center, the periphery being arranged to underlie the edge of the strip of material and support the same adjacent to the fastening-inserting instrumentalities while the curved surface of the thickened center is engaged by the edge of the strip thus cooperating with the closed end of the slot 54 to position the strip as it is fed through the machine. In order to facilitate the adjustment of button gage 70, the latter is clamped to an arm 74 provided with a threaded stem 76 received in a threaded aperture formed in a lug 78 carried at the end of a stem 80. Stem 80 projects from a block 82 slidably mounted in ways 84 carried by an arm 86 projecting from guard plate cap 14. A screw 88 projecting through a slot in arm 86 is utilized to clamp block 82 in adjusted position lengthwise of arm 86 so as to permit the adjustment of button gage 70 toward and from the fastening-inserting instrumentalities. By rotating arm 74 the button gage 70 may be adjusted both transversely of the line of feed of the work and vertically. The amount of vertical movement corresponding to the transverse adjustment which is ever necessary is so small as to be negligible. On the other hand, by rotating arm 74 through one or more complete revolutions any necessary amount of vertical adjustment can readily be obtained. As illustrated, lug 78 is split at 90 and a screw 92 is provided to clamp stem 76 and arm 74 in adjusted position.

While the operation of the device will probably be apparent from the foregoing de-

scription, it may be remarked that as the machine operates awl 10 feeds the work, both the strip and the shoe or shoe part to which it is being attached, through the machine. Thus the awl moves downwardly, pierces the work, moves forwardly and is withdrawn. Then the driver comes down and inserts a fastening in the hole formed by the awl. Slot 54 guides the strip to the awl and driver in the first instance, button gage 70 also assisting in the positioning of the strip and forming a curved abutment about which the strip may be bent as the operator swings the work while operating about a curved edge such as the rear portion of a heel or the toe of a shoe. Thus one edge of the strip is engaged by the closed end of the slot 54 and the other edge of the strip, passing through the open end of the slot, is engaged by button gage 70.

While the invention is illustrated herein as used in connection with the nailing of a continuous strip of randing, it should be understood that it is also applicable to the attachment of individual rands whether molded or otherwise, as well as other strip material such as welting or the like.

Having described the invention, what I claim as new and desire to secure by Letters Patent of the United States is:—

1. Means for controlling a strip of material during the performance of an operation thereon comprising a guide member formed with a slot through which the strip of material passes and a button gage arranged to engage an edge of the strip of material after its passage through said slot.

2. Means for controlling a strip of material during the insertion of fastenings therein comprising a guide member formed with an open-ended slot through which the strip of material passes and a separate gage member arranged to engage and to underlie the edge of the strip of material which passes through the open end of the slot and cooperating with the slotted member to position the strip during the performance of an operation thereon.

3. Means for controlling a strip of material during the performance of an operation thereon comprising a guide member formed with a slot arranged to engage both sides and one edge of a strip of material and a rigidly mounted gage member arranged to underlie a marginal portion of the strip of material and having a surface engaging the other edge of the strip of material to position the material for the performance of an operation thereon.

4. A fastening-inserting machine having a work support, fastening-inserting instrumentalities, a gage arranged to position a shoe in which fastenings are to be inserted, a guide member provided with a slot and arranged to guide a strip of randing to the

fastening-inserting instrumentalities, and another gage member having a curved surface arranged to engage an edge of the rand-
5 ing after its passage through said slot and forming an abutment round which the rand-
ing may be bent as it is fastened to the shoe.

5. A machine for inserting fastenings in shoes having fastening-inserting instru-
10 mentalities, means for guiding a strip of rand-
ing to said instrumentalities, and a gage
member adjacent to said instrumentalities
having a curved surface forming an abut-
ment about which the randing may be bent
15 as it is attached to the shoe.

15. 6. Means for controlling a strip of mate-
rial during the insertion of fastenings there-
in comprising a guide member formed with a
slot having an open end and a closed end and
a button gage located beyond the open end
20 of the slot and arranged to engage the edge

of a strip of material which passes through
the open end of the slot.

7. A machine for inserting fastenings in
shoes having fastening-inserting instrumen-
talities and a gage member forward of said
25 instrumentalities having a curved surface
about which a strip of material may be
progressively bent as it is attached by said
instrumentalities to a work piece.

8. A machine for inserting fastenings in
shoes having fastening-inserting instrumen-
talities and a button gage forward of said
instrumentalities arranged to underlie and
support a strip of material and about which
30 the strip may be progressively bent as it is
attached by said instrumentalities to a work
piece.

In testimony whereof I have signed my
name to this specification.

GEORGE GODDU.
